Edward T. Bell and Daniel T. Bell. Smithfield, Virginia

8329X

Letters Patent

The Schedule referred to in these Letters Patent and making part of the same containing a description of the art of the said Edward T. Bell and Daniel Bell themselves of their improvement in the process of tanning hides and skins.

It all to whom these presents shall come.

Be it known that the Edward T. and Daniel Bell of Smithfield in the County of Jefferson and State of Virginia have invented a new and useful improvement in the process of tanning hides and skins and that the following is full and exact description of the construction and operation of the said improvement as invented by us.

The objects contemplated by our improvement are 1st softening the hides or skins and freeing them from grease &c. 2nd Expanding the hides from the state preparatory to their receiving the tan.

3rd Freeing the tanin or tanning principle from the coarse tan by filtering - 4th causing the tanning liquin more readily to enter the hides or skins by the use of mechanical compression of the hides or skins under the surface of the coarse or out of the coarse thereby shortening the operation.

First, for softening the hides - To every 200 cubic feet of water add $2\frac{1}{2}$ pounds of caustic or unslacked lime (brigated) 10 pounds of carbonate of potash and 1 pound of carbonate of soda. these are made to dissolve by stirring them well. This mixture affords a pure alkaline liquor in which the hides are suspended or immerged in the usual manner and they will become completely softened and the grease neutralized in 24 or 36 hours.

Second for expanding the hides commonly termed raising. To every 200 cubic feet of pure gallic tannin add one pound tannic acid and one pound Sulphuric acid in which suspend or immerse the hides in the usual manner and a complete expansion

will take place in six or eight hours. Third to procure pure tannin tanninum by filtering the roge. When the roge obtained from the bark by any of the usual methods found most convenient either by heat or otherwise has sufficient time to acidify and settle it is thrown upon a filter in form resembling an ash or common tea form hopper with about eight inches of raw cotton at the bottom and sides and then filled in to its top with the fine inner parts of the exhausted bark or refuse tank. This filter should of course be placed in the most convenient position for receiving the roge from the reservoir by a cock and by delivering in like manner the pure tannin tanninum which nearly alone passes through it into the proper vessel from which it is to be drawn for use.

Fourth. The compression of the hides under the surface of the roge or oil of the egg or tannin tanninum. This may be effected in various ways. The method which we have found to be most convenient for compressing under roge is described as follows. A substantial smooth back wooden platform say 16 feet long by 6 feet wide (or the dimensions as also all others, being given may be made to suit the size of the skins, &c.) is constructed and being supported at the ends on strong feet or pillars or mason work so as to raise it about 2 feet from the floor or ground. near its middle and on opposite sides of the platform are placed two rats having a heater in each of sufficient depth and breadth to admit the skins being suspended therein and sunk in the floor so as to bring their top edges six or eight inches above the surface of the platform. The edges of the rats next to the platform being on a level with it and joined thereto water tight (i.e. the rats may be continuous under the platform forming but one vessel and therefore requiring but one heater) so that by the addition of an edge board six or eight inches high laid on the periphery of the platform except where it connects with the rats when they are filled within four or five inches of their highest edges the liquid will have flown over the platform and will stand to the depth of six or three inches upon it. Now in my experiment

To the edges of the platform that adjoins the water two ways or guides are constructed on the upper surface thereof and running its whole length readily. These guides are intended to direct the rollers herein after mentioned and at both ends of each are small leading pulleys for uses hereafter explained. Two wooden brass or copper rollers often or twelve inches diameter and of a length equal to the distance between the guides are placed crosswise on the platform their journals (if wooden rollers) should be brass or copper and are to be fixed in two substantial wooden bridges or end pieces upon which latter are raised two upright cross frames which serve as bearings to support a heavy weight (which may be diminished or altogether dispensed with in case metallic rollers are used) placed on a floor that joins these upright angles also at the centre of each of these bridges and on their outside an arm is formed let in and firmly secured which descends to within a short distance of the surface of the platform for the purpose of attaching four strong cords, two to each arm, that run in opposite directions along the outside of the guides, to the leading pulleys above mentioned. Their use being to draw the rollers and their incumbent weight back and forth on the platform. At each end of the platform and immediately behind the leading pulleys uprights are raised that form the bearings of two transverse shafts having a pulley on each end inside of the bearings placed in a line with the leading pulleys above mentioned to which the cords above mentioned are attached and around which they are wound up at one end of the platform at the same time that they unwind at the other by which contrivance by turning two cranks placed on the extremities of each shaft the shaft may be put in motion and the rollers and weight drawn alternately from one end of the platform to the other with great facility, for the purpose of flattening up the slack of the cords additional cords are attached to the centre of the shafts each of which after two or three turns run round the shafts passing upward over a small shelf on the upper extremity of a small post raised

from the end of the platform descending on the other side and has a sufficient weight attached thereto. Operation. The vats on either side of the platform are filled to within 4 or 6 inches with the tanning liquor (obtained as above directed) which by means of the heaters are raised to 48° degrees of Farenheit - or blood heat the temperature which we apply to the sides in all the instances herein described. The sides after being prepared for tanning are suspended therein, then such taken in its turn and one or more spread out smoothly on the platform between the guides the rollers are passed over it on them back and forth (varying its. or their position if necessary) a number of times, proportional to its thickness or their thickness, by which operation any watery or foreign substance that may occupy its or their pores are pressed out it or they are then drawn over the edges of the platform without lifting out of the liquor which must be avoided as much as possible (if pressed under oozes) and suspended in the vat where they are suffered to expand which they do in 6 or 8 hours and by the act of expansion or swelling the pores and ducts are charged with the tanning liquor which having deposited its tannin the succeeding pressure of the rollers expels the exhausted or watery fluid that now only remains and prepares them to receive a fresh charge, and so with every compression and expansion until the process of tanning is completed or so much of it as that liquor is deemed capable of performing. After which it or they are taken to a stronger, where they are treated in like manner, and thence again to a stronger until the operation is finished which for heavy leather takes place in 6 or 8 weeks, and for light skins from 6 to 12 days. For the purpose of economising time and labour we place a series of platforms & vats in their continuation so as to enable the workmen to commence the operation at the first or weakest, which should mark from 1 to 2 degrees on the hydrometer, and bring the sides out perfectly turned at the last or strongest marking from 6 to 8 degrees. However little experience and observation will point out the best practical course, better than any written direction on the subject. It is necessary to remark that the weight used for compression must be proportional to the thickness of the hide and be light.

and the tanning process. This also must be committed to the judgment of the operator. Now what we claim as new and our invention is. First. The mixture or compound of the ingredients, as herein described, for softening the hides and neutralizing the grease. Second. The mixture or compound of the ingredients as herein described for expanding or swelling the hides preparatory to receiving the tanning liquor. Third. The procuring the pure tanning liquor by filtering the ore as herein described. Fourth. The compressing the hides separately or collectively by mechanical means under the ore or out of the ore and suffering them to expand alternately so as to cause the tanning liquor to enter and to expell it when exhausted and also the apparatus or machine herein described to be used for that purpose.

In testimony that the foregoing is a true description of our said invention or improvement we have this unto subscribe our names this 22nd day of July 1834.
